(57) **CLAIM**

The ornamental design for a tangential flow filtration cassette as shown and described.

DESCRIPTION

FIG. 1 is an isometric view of a tangential flow filtration cassette according to an embodiment of the present invention;

FIG. 2 is a front view thereof;

FIG. 3 is rear view thereof;

FIG. 4 is an end view thereof;

FIG. 5 is an opposite end view thereof;

FIG. 6 is a top view thereof;

FIG. 7 is a bottom view thereof;

FIG. 8 is an isometric view of a tangential flow filtration cassette according to another embodiment of the present invention;

FIG. 9 is a front view thereof;

FIG. 10 is rear view thereof;

FIG. 11 is an end view thereof;

FIG. 12 is an opposite end view thereof;

FIG. 13 is a top view thereof;

FIG. 14 is a bottom view thereof;

FIG. 15 is an isometric view of a tangential flow filtration cassette according to another embodiment of the present invention;

FIG. 16 is a front view thereof;

FIG. 17 is rear view thereof;

FIG. 18 is an end view thereof;

FIG. 19 is an opposite end view thereof;

FIG. 20 is a top view thereof;

FIG. 21 is a bottom view thereof;

FIG. 22 is an isometric view of a tangential flow filtration cassette according to another embodiment of the present invention;

FIG. 23 is a front view thereof;

FIG. 24 is rear view thereof;

FIG. 25 is an end view thereof;

FIG. 26 is an opposite end view thereof;

FIG. 27 is a top view thereof; and,

(Continued)

FIG. 28 is a bottom view thereof.
The broken lines illustrate portions of the tangential flow
filtration cassette that form no part of the claimed design.
